UNITED STATES PATENT OFFICE.

WILLIAM M. DOERING AND CHARLES J. DOERING, OF CINCINNATI, OHIO.

CONTAINER AND DISPLAY-CARTON.

1,390,196.

Specification of Letters Patent. Patented Sept. 6, 1921.

Application filed February 27, 1919. Serial No. 279,483.

To all whom it may concern:

Be it known that we, WILLIAM M. DOERING and CHARLES J. DOERING, citizens of the United States, and residing at Cincinnati, in the county of Hamilton and State of Ohio, have invented a new and useful Improvement in Containers and Display-Cartons, of which the following specification is a full disclosure.

10 Our invention relates to a combined display carton and container.

The object is to provide a cardboard box with an attached front folding display panel, and an ornamental holding arch or crown to 15 constitute the open-up formation.

The features of the invention are more fully set forth in the description of the accompanying drawings, forming a part of this specification, in which:

20 Figure 1 is a perspective view of the carton.

Fig. 2 is a section on line 2, 2, Fig. 1, the hinged back being shown in partly open position, in dotted lines.

25 Fig. 3 is a front elevation with the cover removed.

Fig. 4 is a plan section on line 4, 4, Fig. 1.

Fig. 5 is a front elevation of the upper portion of the carton as set up for display 30 purposes.

Fig. 6 is a similar front elevation of the lower portion of a modified form of carton adapted for supporting an article of merchandise.

35 Fig. 7 is a top plan view of the carton shown in Fig. 5.

Fig. 8 is a detail section on line 8, 8, Fig. 6.

In the drawings, we have shown two forms, that shown in Figs. 1, 2, 3, 4, 5 and 7 showing the advertising medium adhesively attached to or integral with the base of the box.

45 In this form, 1 is the rectangular box, with a lid 2, hinged to the top edge of one end of the box, see Fig. 2. On the bottom of the box is secured the medial panel 3, having the right and left folding wings 4, 5, hinged thereto. A top cross-piece or arch 6 is provided having bottom notches 7 engaging with the notches 8 at the upper margins of the wings 4, 5.

50 In shipping, the arch is held flat between the wings and a detached cover 12 is engaged over the box and folded wings.

55 In display formation, the arch is bridged across the angularly extended wings, forming

ing an ornamental top piece projected forwardly of the medial panel, holding the advertising member rigid, and producing a very simple and attractive display.

60

The knock-down or shipping formation is shown in Figs. 1, 2, 3, and 4. In Figs. 6 and 8 the modification provides a medial panel 9, and folding or extensible strips 10 joining the ends of the box with the top and bottom 65 of the display panel, enabling the panel to be folded flat against a wall of the box for shipping or to be projected beyond the box for display. The wings and arch are as in the first described form. In this modified 70 form, preferably, the box is open at the top and has a separable top lid, though this is inconsequential. The functional utility of the modified form is, that it enables the medial panel, standing away from the box, 75 to be formed with cut-out portions constituting means for displaying the wares, such as rubber articles, or the like, to be tucked into these holding and display formations.

The device is simple, cheap, ornamental, 80 useful and a desirable combined container and advertising medium.

Having described the invention, we claim:

1. A display card and box support consisting of a cardboard box, a panel display 85 member attached to one wall of the box, right and left hand display wing members hinged to the opposite edges of the panel member, and a top display member bridging and detachably engaging the wings in a plane in 90 front of and parallel with the panel member.

2. A display card and box support consisting of a cardboard box, a panel display member, extensible strips attached respectively to corresponding margins of the box 95 and panel, enabling the panel to be folded flat against a wall of the box for shipping, or to be projected beyond the body of the box for displaying, right and left hand displaying members hinged to opposite margins 100 of the panel member, and a top display member bridging and detachably engaging the wings in a plane in front of and parallel with the panel member.

3. A display card and box support consisting of a cardboard box, a panel display member, extensible strips attached respectively to corresponding margins of the box and panel, enabling the panel to be folded flat against a wall of the box for shipping, or 110 to be projected beyond the body of the box for displaying, right and left hand display-

ing members hinged to opposite margins of the panel member, and a top display member bridging and detachably engaging the wings in a plane in front of and parallel with the panel member, said panel member having cut-out portions forming means for supporting and displaying the container wares.

In witness whereof we hereunto subscribe our names, as attested by the two subscribing ¹⁰ witnesses.

WILLIAM M. DOERING.
CHARLES J. DOERING.
